UNITED STATES PATENT OFFICE

2,577,329

ADJUSTABLE CONCAVE

Houston N. Irvine, Burlington, Iowa, assignor to
 J. I. Case Company, Racine, Wis., a corporation
 of Wisconsin

Application June 7, 1946, Serial No. 675,162

5 Claims. (Cl. 130—27)

1

My invention relates to adjustable concavities. One of the objects of my invention is to provide in a thresher cylinder and concave co-operating therewith, improved means for supporting the concave for adjustment toward and from the axis of the cylinder comprising adjustable means for supporting the front portion of the concave, adjustable means for supporting the rear portion of the concave, and common means for adjusting both said adjustable means simultaneously.

A further object is to provide in such a construction means for adjusting one of said adjustable means independently of the other.

A further object of my invention is to provide such a construction in which each of the adjustable means comprises a rock lever having an arm engaging the concave and in which a link is provided pivotally connecting the other arms of the levers together.

A further object is to provide improved means for mounting the concave bars in the concave frame.

A further object is to provide a concave construction in which the concave bars may be turned upside down to bring a different wear face into operative relation to the rub bars.

A further object is to provide an improved concave construction in which improved means are provided for clamping the concave bars in place in the concave frame.

Further objects and advantages of the invention will be apparent from the description and claims.

In the drawings, in which my invention is illustrated,

Figure 1 is a plan view of a concave and associated parts;

Fig. 2 is a section substantially on the line 2—2 of Fig. 1;

Fig. 3 is a front elevational view as seen from the left of Fig. 2, and

Fig. 4 is a section substantially on the line 4—4 of Fig. 2.

Referring to the drawings in detail, the construction shown comprises a rotatable cylinder 1 having the rub bars 2 for co-operation with the concave bars 3. The concave bars 3 are mounted in a frame 4 which is provided with means for supporting it for adjustment toward and from the axis of the cylinder. This concave frame comprises two lateral cheek pieces 4^a spaced apart substantially the length of the concave bars and secured together by means of a front spacing and supporting pipe 4^b, the opposite ends 55

2

of which are secured to the cheek pieces, respectively, and by a rear spacing and supporting bar 4^c extending between the cheek pieces 4^a and having its ends secured to the cheek pieces, respectively. Means are provided for adjusting both ends of the concave frame 4 simultaneously or for adjusting one end of the frame independently of the other.

The adjusting means for the rear end of the frame comprises a rock bar 5 rotatably mounted in eye bolts 6 and having rock arms 7, one at each end thereof mounted thereon and engaging slots 8 in the cheek pieces 4^a, respectively. The adjusting means for the front end of the concave or frame 4 comprises a rock bar 10 rotatably mounted in eye bolts 11 secured to the supporting bars 11^a and provided with rock arms 12, the ends of which extend outwardly and engage in slots 13 in the cheek pieces 4^a, respectively. As shown in Figs. 2 and 3, the eyebolts 6 and 11 may be adjusted up and down with respect to the supporting bars 11^a by adjusting the lock nuts 11^b.

In order to insure radial movement of the concave carrying cheeks with respect to the axis 25 of the cylinder and holding it against circumferential movement, each of the cheeks is provided with a guide pin 14 which extends into a guide slot 15 in a suitable guide block 15^a secured to the frame 4.

In order to provide for simultaneous operation of the rock arms 7 and 12 for the front and rear ends of the concave cheeks, the rear rock bar 5 has a rock arm 16 secured thereto which is connected by link 17 with a rock arm 18 secured to the front rock bar 10. A rock lever 19 is formed integral with the rear rock arm 16. This lever 19 may be adjusted and held in any one of a number of adjusted positions by an operating bar 19^a pivoted to the lever and having a plurality of notches for selective engagement with a slotted retaining plate 20.

With this construction, when the operating lever 19 is moved, it will rock the rear shaft 5 and this will rock the front shaft 10 by means of the link 17 connecting the two rock arms 16 and 18. If the control lever 19 is rocked counterclockwise, as viewed in Fig. 2, the rock arm 7 will be moved counterclockwise and the rear ends of the concave cheeks 4^a will be moved away from the cylinder 2. As the rear rockshaft 5 is rocked counterclockwise, the forward rockshaft 10 will be rocked in a clockwise direction because of the link 17 connecting the lower end of the rear rock arm 16 with the upper end of the front rock arm

18. Thus the front ends of the cheek plates 4^a also will be moved away from the cylinder.

In order to effect adjustment of the front end of the concave cheek plates 4^a independently of the adjustment of the rear ends of the cheek plates 4^a, means are provided for changing the effective length of the link 17 connecting the two rock arms. For this purpose, the front end of the link is made to extend through a trunnion block 21 having a pivotal connection with the rock arm 18, and a pair of adjusting nuts 22^a and 22^b are threaded on the link 17, one on each side of the trunnion block 21, so that by adjusting these nuts the distance between the pivot pin 23 for the front rock arm 18 and the pivot pin 24 for the rear rock arm 18 may be adjusted. This will enable independent adjustment of the front and rear ends of the concave carrying cheek plates 4^a.

The concave itself comprises in addition to the cheek pieces 4^a and connecting bars 4^b and 4^c a plurality of concave bars 3 extending between the cheek pieces 4^a and a plurality of spacer channels 26 extending between the concave bars 3 and guiding the straw as it is advanced by the rub bars 2. The ends of the concave bars 3, as well as the ends of the channels 26, extend into generally arcuate grooves 27 in the inner faces of the cheek pieces 4^a so that the bars 3 and channels 26 can be inserted at the front ends of the cheek pieces 4^a and pushed or slid rearwardly into their final position.

The concave bars 3 are shown as substantially rectangular in cross section. When these concave bars are in position with respect to the cylinder, the hardest wear will be on the upper front edge of the concave bar. The design of the concave bars is such that any one of the four corner edges 25^a, 25^b, 25^c and 25^d of the concave bar may be brought into the position of extreme wear. To bring a different edge of the concave bar into the position of extreme wear, it may either be turned end for end with respect to the cheek pieces or it may be turned upside down.

Each concave bar may be so designed that the upper edge of the concave bar and the lower edge of the concave bar are differently offset with respect to the portion of the bar which extends into the groove 27 in the cheek piece, as shown in Fig. 4. With this construction, turning the bar upside down will change the spacing between the wearing edge of the concave bar 3 and the rub bars 2 on the cylinder and will also change the level of the wearing edge with respect to the straw guide bar 26.

In order to brace the channel members, U-shaped clips 28 may be provided having flange portions 28^a which may be spotwelded or otherwise secured to the flanges 29 of the channel members. In order to hold the channel members in position with respect to the concave bars, each bar 3 may have a pin 30 inserted therethrough, the opposite ends of which engage registering openings in the flanges 28^a of the adjacent channel members 26. One or more of these positioning pins may be provided in the central portion of the concave bar. These pins 30 and registering openings are engageable by relative lateral movement of the bars and constitute interfitting means for supporting the grate bars against relative radial movement. The usual grate fingers 31 may be secured to the channel 4^c extending between and secured to the rear ends of the cheek plates 4^a.

For clamping the concave bars 3 and spacing

channels 26 in place after they have been slipped into the grooves in the cheek pieces 4^a, a pair of adjusting bolts 32 are provided, one adjacent each cheek piece, each bolt 32 being threaded through a cylindrical pin 33 extending into the cross pipe 4^b secured to the cheek pieces 4^a and having its point engaging the foremost one of the concave bars 3. By screwing in on these adjusting bolts 32, the entire assembly of concave bars 3 and spacing channels 26 will be forced rearwardly toward the back stop channel bar 4^c and the entire series will be thus firmly clamped in position. For holding the bolts 32 in adjusted position, lock nuts 34 may be provided threaded into the bolts and locking against the cross pipe 4^b.

Further modifications will be apparent to those skilled in the art and it is desired, therefore, that the invention be limited only by the scope of the appended claims.

Having thus described my invention, what I claim and desire to secure by Letters Patent is:

1. In a cylinder and concave construction, a plurality of grate bars, a plurality of straw-guiding bars interposed between said grate bars, and a pair of cheek pieces for supporting the ends of the grate bars and straw-guiding bars, said straw guiding bars being substantially coextensive longitudinally with respect to said grate bars and wide enough to bridge the space between the grate bars, said grate bars being substantially flat and of greater height than thickness, said straw-guiding bars having downwardly-extending flanges engaging and positioning the flat sides of the grate bars, the portions of said grate bars and straw-guiding bars intermediate the cheek pieces having interfitting means whereby the grate bars and the straw-guiding bars are supported against relative radial movement with respect to the cylinder axis comprising pins on the grate bars extending through holes in the flanges, at least a portion of said interfitting means being spaced a substantial distance from said cheek pieces.

2. In a cylinder and concave construction, a plurality of grate bars, a plurality of straw-guiding bars interposed between said grate bars, and a pair of cheek pieces for supporting the ends of the grate bars and straw-guiding bars, said straw-guiding bars being substantially coextensive longitudinally with respect to said grate bars and wide enough to bridge the space between grate bars, said grate bars being substantially flat and of greater height than thickness, said straw-guiding bars having flat side portions for engaging and positioning the flat sides of the grate bars, each of said grate bars having four threshing edges, one at each corner of the bar, each of said grate bars having quick detachable variable position adjusting means including lugs offset with respect to the medial plane of the grate bars for mounting it in said cheek pieces so as to bring any one of its threshing edges into cooperative relation with respect to the cylinder, by turning it upside down or by turning it upside down and end for end.

3. In a thresher cylinder and concave construction a rigid arcuate concave and means for moving and guiding said concave as a unit for adjustment toward and from the axis of the cylinder comprising means for adjusting the front portion of the concave radially toward and from the cylinder, means for adjusting the rear portion of the concave radially toward and from the cylinder, and pin and slot means for guiding said

concave in its adjusting movement toward and from the cylinder enabling floating movement of the concave radially toward and from the cylinder and holding it against circumferential movement with respect to the cylinder, each of said adjusting means comprising a rock arm rotatable about a fixed axis having a pin engaging a slot in the concave, said front and rear rock arm slots extending substantially in the same general direction substantially tangentially with respect to the cylinder and said guide slot extending transversely with respect to the slots in the concave and substantially radially with respect to the axis of the cylinder, said moving means comprising force transmission means acting between said rock arms.

4. In a thresher cylinder and concave construction a rigid arcuate concave and means for moving and guiding said concave as a unit for adjustment toward and from the axis of the cylinder comprising means for adjusting the front portion of the concave radially toward and from the cylinder, means for adjusting the rear portion of the concave radially toward and from the cylinder, and pin and slot means for guiding said concave in its adjusting movement toward and from the cylinder enabling floating movement of the concave radially toward and from the cylinder and holding it against circumferential movement with respect to the cylinder, each of said adjusting means comprising a rock arm rotatable about a fixed axis having a pin engaging a slot in the concave, said front and rear rock arm slots extending substantially in the same general direction substantially tangentially with respect to the cylinder and said guide slot extending transversely with respect to the slots in the concave and substantially radially with respect to the axis of the cylinder, said moving means comprising common means for actuating the rock arms.

5. In a cylinder and concave construction, a plurality of grate bars, a plurality of straw-guiding bars interposed between said grate bars, and a pair of cheek pieces for supporting the ends of the grate bars and straw-guiding bars, said straw-

guiding bars being substantially coextensive longitudinally with respect to said grate bars and wide enough to bridge the space between grate bars, said grate bars being substantially flat and of greater height than thickness, said straw-guiding bars having flat side portions for engaging and positioning the flat side of the grate bars, each of said grate bars having two threshing edges at diagonally opposite corners thereof, each of said grate bars having quick detachable variable position adjusting means including a tongue and groove connection offset with respect to a horizontal plane through the medial axis of the grate bar for mounting it in said cheek pieces so as to bring either of said threshing edges into cooperative relation with respect to the cylinder by turning it upside down.
